US00D996696S

(12) **United States Design Patent** (10) **Patent No.:** **US D996,696 S**
(45) **Date of Patent:** **** Aug. 22, 2023**

(54) **LIGHT FIXTURE**

- (71) Applicant: **HGCI, Inc.**, Las Vegas, NV (US)
(72) Inventor: **Christopher Reynolds**, Vancouver, WA (US)
(73) Assignee: **HGCI, Inc.**, Las Vegas, NV (US)
(**) Term: **15 Years**
(21) Appl. No.: **29/749,549**
(22) Filed: **Sep. 7, 2020**

Related U.S. Application Data

- (63) Continuation of application No. 29/718,572, filed on Dec. 26, 2019, now Pat. No. Des. 895,891, which is (Continued)

(57) **CLAIM**

The ornamental design for a light fixture, as shown and described.

DESCRIPTION

FIG. 1 is a perspective view of a light fixture, as viewed from above, showing my new design;
FIG. 2 is a perspective view of the light fixture shown in FIG. 1, as viewed from below;
FIG. 3 is a left side view of the light fixture shown in FIG. 1;
FIG. 4 is a right side view of the light fixture shown in FIG. 1;
FIG. 5 is a front elevation view of the light fixture shown in FIG. 1;
FIG. 6 is a rear elevation view of the light fixture shown in FIG. 1;
FIG. 7 is a bottom plan view of the light fixture shown in FIG. 1; and,
FIG. 8 is a top plan view of the light fixture shown in FIG. 1.

The broken-line disclosure shown in the views is understood to represent portions of the article in which the claimed design is embodied, but which form no part of the claimed design.

1 Claim, 6 Drawing Sheets

Related U.S. Application Data

a continuation of application No. 29/624,120, filed on Oct. 30, 2017, now Pat. No. Des. 871,654.
